UNITED STATES PATENT OFFICE.

CHARLES E. SEMPLE, JR., OF YOUNGSTOWN, OHIO.

REPRODUCER FOR LATERAL-CUT RECORDS.

Application filed February 14, 1924. Serial No. 692,888.

To all whom it may concern:

Be it known that I, CHARLES E. SEMPLE, Jr., citizen of the United States, residing at Youngstown, in the county of Mahoning and

5 State of Ohio, have invented certain new and useful Improvements in Reproducers for Lateral-Cut Records, of which the following is a specification.

This invention relates to reproducers for 10 phonographs and the like and has particular reference to an improved stylus or needle bar construction and mounting therefor.

A primary object of the invention is to provide a construction which is particularly 15 adapted for use in connection with lateral cut records. In that connection the invention embodies a stylus or needle bar which is coordinated with the diaphragm in such a manner as to eliminate undue strain upon 20 the latter and without hindering the free movement of the stylus or needle bar.

Another object is to provide novel means for imparting balanced tensioning forces to 25 said diaphragm according to the principle of my prior Patent No. 1,480,786, dated Jan. 15, 1924.

With the above and other objects in view which will more readily appear as the nature 30 of the invention is better understood, the same consists in the novel construction, combination and arrangement of parts herein- 35 after more fully described, illustrated and claimed.

A preferred and practical embodiment of 35 the invention is shown in the accompanying drawings, in which:

Figure 1 is a front elevation of a reproducer constructed in accordance with my invention.

40 Figure 2 is an end elevation thereof looking in the direction indicated by the arrows on line 2—2 of Figure 1.

Figure 3 is an elevation partly in section looking in the direction of the arrows on line 45 3—3 of Figure 1, and

Figure 4 is a detail view looking in the direction of the arrows on line 4—4 of Figure 1.

Similar reference characters designate cor- 50 responding parts throughout the several figures of the drawings.

The present invention carries into effect, in a reproducer for lateral cut records, the same general theory of the stylus or needle bar construction set forth in my former patent wherein a reproducer for vertical cut

records is shown. That is, I propose to use a bar which is of special formation in cross-section to add stiffness, and to provide a connection between said bar and the diaphragm whereby balanced tensioning forces will be applied thereto. Thus, the stylus or needle bar is connected with the diaphragm in unitary relation with each other, while at the same time the necessary freedom of action of the diaphragm at all points of oscillation will be permitted and without imposing any undue strains on the diaphragm due to the tensioning of the stylus or the needle bar.

In the specific embodiment of my present invention as shown in the accompanying drawings, I have interposed directly between the needle bar and the diaphragm, a yieldable connection for imparting opposed tensioning forces to said diaphragm.

The present device includes in its organization a frame A for supporting a lateral cut record and containing a diaphragm B, a bridge C connected to the frame, a stylus or needle bar D carried by the bridge, and a yieldable connection E between the needle bar and the diaphragm. The needle bar is provided with a needle holder so arranged as to support the needle in a plane parallel to the general plane of the diaphragm and at a suitable angle to the plane of the record so as to permit the reproducer to function with lateral cut records.

The bridge C extends tangentially across the frame and over the diaphragm B. The needle bar D is pivoted to the bridge C to rock longitudinally about an axis disposed in a plane parallel to the plane of the diaphragm B, and is formed from an elongated bar of metal which is preferably rectangular in cross-section. The bridge C is provided on its under face with a pair of spaced pivot points 5—5 preferably of conical formation, while the needle bar D is provided with fulcrum seats 6—6 which receive the pivot points so as to permit the bar to rock about its longitudinal axis.

In order to retain the needle bar on its fulcrum I have provided a keeper 7 which consists of a strip of metal having one end secured by a clamp 8 to one end of the needle bar. This plate is bent intermediate its ends to provide a free end portion which extends under and parallels the needle bar, and the extreme end thereof is bent upwardly as at 9 to form a keeper finger 10.

This finger terminates in a pointed end and is disposed in a seat 11 formed in the needle bar. The point of engagement between the finger 10 and the needle bar is in a line containing the pivots 5—5, and as a result, the needle bar will be free to oscillate about its longitudinal axis. The lower end of the needle bar is formed with a depending needle holder 12 for supporting a needle N in a plane parallel to the plane of the diaphragm B and at an angle of approximately 45° to the horizontal plane of the lateral cut record. A clamping screw 13 is associated with the holder to secure the needle 15 in position therein.

Secured to the needle bar D and extending through an opening 14 in the bridge C is a needle arm 15, which is of substantially U-shaped or channel formation and 20 may be made of a comparatively soft metal. This arm extends radially relative to the diaphragm B and has its free end terminating at a point substantially above the center thereof.

25 In order to coordinate the needle bar with the diaphragm in such a manner as to retain both elements in tension relation without subjecting the diaphragm to undue strain or impeding the free action of the needle bar I have provided the connection E. This connection includes a link rod 16 which extends through an opening 17 formed in the diaphragm B, the inner end of the link rod is threaded for engagement with a clamping nut 18. Disposed between said nut and the diaphragm is a clamping element 19 which in this instance comprises a disk 20 and one or more soft washers 21, the latter being disposed between the disk 20 and the diaphragm. Disposed against the outer face of the diaphragm is an outer clamping element 22 which in this instance consists of a non-metallic disk 23 and a pad or washer 24 of soft material, said washer being disposed between the disk 23 and the outer face of the diaphragm. The outer end portion of the link rod 16 is preferably flattened and is formed with an eye 25 through which the free end of the needle arm 15 extends. Disposed between the free end of the needle arm 15 and the outer clamping element 22 is a spring 26. This spring is formed from a single length of wire which is centrally bent inwardly to form a seat 27 for receiving the needle arm 15. Thus the spring 28 is bent to form parallel curved arms 28—28 and these arms are bent at their ends to form feet 29—29 and respectively engaging openings 30—30 formed in the disk 23 of the outer clamping device, said openings being respectively disposed on opposite sides of the link rod 16. This spring which engages the needle arm 15 exerts a pressure 35 on said arm in the direction away from the

diaphragm B and the arm through the eye 25 will cause an outward pressure to be exerted on the inner clamping element 19, at the same time the spring 26 urges the outer clamping element against the diaphragm. 70 Consequently, the yieldable connection just described imparts opposed tensioning forces to the diaphragm.

Thus I have provided a reproducer which is especially adapted for use in connection 75 with lateral cut records and in which there is provided a needle bar construction and mounting which is connected with the diaphragm in a manner to clarify the tone by increasing the sensitiveness of the connection between the diaphragm and the needle bar.

Without further description, it is thought that the features and advantages of the invention will be readily apparent to those 85 skilled in the art and it will, of course, be understood that the changes in the form, proportion and minor details of construction may be resorted to within the scope of the appended claims. 90

I claim:

1. A sound reproducer of the class described including a diaphragm, a needle bar, a connection between the needle bar and the diaphragm comprising clamping devices respectively disposed against the inner and outer faces of said diaphragm, and a link rod extending outwardly from the inner clamping device through the diaphragm and the outer clamping device and having its outer end connected with the arm of said needle bar, and a spring interposed between the outer clamping device and the arm for imparting opposing tensioning forces to the diaphragm, said spring being formed from 95 a single length of wire bent intermediate its ends to form curved arms, the connecting portion between the arms being disposed against the arm of the needle bar and the free ends of the spring engaging the outer 100 clamping device. 105

2. A sound reproducer of the class described including a diaphragm, a needle bar, a connection between the needle bar and the diaphragm comprising clamping devices respectively disposed against the inner and outer faces of said diaphragm, and a link rod extending outwardly from the inner clamping device through the diaphragm and the outer clamping device and having its outer end connected with the arm of said needle bar, and a spring interposed between the outer clamping device and the arm for imparting opposing tensioning forces to the diaphragm, said spring being formed from 115 a single length of wire bent intermediate its ends to form curved arms, the connecting portion between the arms being bowed inwardly towards the diaphragm to form a 120 seat for receiving the arm of the needle bar 130

and the free ends of the spring engaging the outer clamping device.

3. A sound reproducer of the class described including a diaphragm, a needle bar, 5 a connection between the needle bar and the diaphragm comprising clamping devices respectively disposed against the inner and outer faces of said diaphragm, a link rod extending outwardly from the inner clamping 10 device through the diaphragm and the outer clamping device and having its outer end connected with the arm of said needle bar, and a spring interposed between the outer clamping device and the arm for imparting opposing tensioning forces to the 15 diaphragm, the outer clamping device having a pair of seats respectively located on opposite sides of said link rod, said spring being formed from a single length of wire 20 bent intermediate its ends to form curved arms, the connecting portion between the arms being disposed on the arm of the needle bar and the free ends of the spring engaging the seats of the outer clamping device.

25 4. A sound reproducer of the class described including a diaphragm, a needle bar, a connection between the needle bar and the diaphragm comprising clamping devices respectively disposed against the inner and 30 outer faces of said diaphragm, and a link rod extending outwardly from the inner

clamping device through the diaphragm and the outer clamping device and having its outer end connected with said needle bar, and a spring interposed between the outer 35 clamping device and the needle bar.

5. In a reproducer of the class described, a diaphragm, a support, a bar mounted on said support to rock transversely on its longitudinal center, means for yieldingly holding said bar to said support, a needle clamping device projecting laterally from one face of the bar and at one end thereof, and an arm projecting from the other face of the bar and at the opposite end thereof, and a connection 40 45 between said arm and the diaphragm.

6. In a reproducer of the class described, a diaphragm, a support, a bar mounted on said support and adapted to rock transversely on its longitudinal center, a spring 50 for yieldingly maintaining said bar against the support, means provided from one face of the bar to hold a needle, and means provided from another face of the bar for imparting movement imparted to said bar by the needle clamping means to the diaphragm, said means including an arm and the connection between said arm and the diaphragm.

In testimony whereof I hereunto affix my signature.

CHARLES E. SEMPLE, JR.
